UNITED STATES PATENT OFFICE.

JOHN T. QUIGLEY, OF LOS ANGELES, CALIFORNIA.

FILING SYSTEM.

Application filed March 29, 1926. Serial No. 98,186.

This invention relates to a vertical filing system and equipment and has improvements in the identification means applied to the vertical sheets or folders used for separating or receiving letters and other documents in vertical form.

The chief objects of the invention are to shorten the time required to find a specified document in a vertical file, to simplify a vertical file, and reduce the expense necessary in making the same.

One feature of the invention consists in providing for a vertical filing system having a receptacle, vertically disposed card-like sheets or folders therefor, all similarly formed and each having an indentation in the top thereof near one end and a removable label folded down over the top near the other end thereof, with indicia on both the front and the back of the label adjacent the top thereof, the indicia being duplicated in reverse order on the front and the back of the label, whereby said sheets or folders may be filed in two positions, one position having the indentations in the sheets near one side of the receptacle and in the other position the sheets being reversed with the indentations near the other side of the receptacle. This enables the sheets to be reversed and the indicia to be read from the front and also from the rear and the indicia will be visible through the indentations of the sheet or sheets in front of it, whether viewed from the front or rear.

Another feature of the invention consists in providing a label, preferably with four equilateral sides, and creased diagonally and centrally, folded over the top of the sheet and the two opposite ends or tips thereof inserted in opposite directions through a slit in the sheet or folder below the top of the sheet in a manner which securely holds the label in place, so the label does not project above the top of the sheet or folder, but lies snugly thereon.

In carrying out the invention I preferably employ folders with the rear leaf of each folder extending above the front leaf and the top of the rear leaf has an indentation near one end in the top of the leaf and the index marking is located on both sides and in reverse position and this index marking is preferably on a label folded over the top of the higher leaf of the folder with its ends

inserted through a slit in such leaf of the folder.

The full nature of this invention will be understood from the accompanying drawings and the description and claims.

In the drawings:

Figure 1 is a front perspective view of a file drawer filled with folders made and labeled according to this invention, the same being centrally broken away to reduce the size of the figure; Fig. 2 is a rear perspective view of what is shown in Fig. 1; Fig. 3 is a perspective view of a folder in open position; Fig. 4 is a plan view of the square form of label before it is folded or mounted and with indicia printed thereon; Fig. 5 is a plan view of a rhombus-form of such label, modifications thereof being indicated by dotted lines; Fig. 6 is a perspective view of the label shown in Fig. 5 after it has been folded but is partly in open position; Fig. 7 is a central vertical section through the upper part of a sheet or folder and a label showing the position of the label after the first step in the process in mounting it on the sheet or folder; Fig. 8 is the same as Fig. 7 showing the condition of the label after the second step in the process of mounting; Fig. 9 is the same as Fig. 8 showing the position of the label after the third step in mounting; Fig. 10 is the same as Fig. 9 with the label in position after it is fully mounted; Fig. 11 is a rear elevation of a sheet or folder in finished form ready to file; Fig. 12 is a view of the front side of the folder shown in Fig. 11; and Fig. 13 is a front elevation of two labeled folders assembled as they would be in the filing drawer, the rear folder having its ends reversed as compared with the front folder.

The invention as shown in the drawings herein for the purpose of illustrating the general nature thereof discloses a vertical file containing folders, but some features of the invention are not necessarily limited to folders as sheets or cards may be used instead of folders, but the preferable form of the invention is as herein shown.

As appears in Figs. 1 and 2 there is a drawer or receptacle having a front 10, sides 11, and rear 12. In this receptacle or drawer there is a series of vertically disposed folders 13, formed and filed or arranged as herein-after explained.

The folder 13 is a simple and convenient vertical filing device consisting of a single sheet having a transverse fold to provide two vertical leaves 131 and 132 of unequal height. The leaf 132 is usually about one-half inch higher than the leaf 131, as seen in Figs. 3 and 12. Folders in vertical files are assembled in a drawer with their folds resting on the bottom of the drawer and 10 their top edges extending above the sides of the drawer and forming the visible portion of the file.

The foregoing arrangement is old in the art of vertical filing and the novel features 15 of the invention will now be explained.

The folder 13 is preferably what is called square cut, having the back leaf 132 higher than the front leaf 131, as indicated in Fig. 11. In the top of the high leaf of the 20 folder there is an indentation 14 cut out as long as the indices may require, say two or three inches, and near one end of the folder to one side of the middle thereof. The depth of the indentation is sufficient to expose 25 to view the inscription placed on a folder to the rear.

In the other end of the folder, a short distance from the top edge of the high leaf there is a substantially horizontal slit 15 30 which may be an inch or more long, and over the top of such end of the high leaf of the folder a label 16 is folded and secured in said slit for receiving indices. This slit preferably is made by an incision in the material of the folder which removes no stock but leaves the edges in contact. The resulting friction of the abutting edges serves to lock and hold the material of the inserted label in place. As heretofore explained, 35 said indices and label should be substantially the same distance from one end of the folder as the indentation is from the other end in order that when the folders are placed in reverse position, one behind the other, the label and index shall appear through and behind the indentation of a preceding folder.

The label 16 may be of any thin and flexible sheet material and may be in any desired shape, but preferably with equilateral 50 sides, so that it has oppositely located ends, tips or corners 17 to be inserted through the slit 15. The preferable form is that shown in Fig. 4, which is a rectangular sheet of paper, and it is scored or folded centrally and diagonally at 18, and when folded it 55 appears substantially as shown in Fig. 6.

Another form of label is shown in Fig. 5, as a rhombus-shaped label 19 cut out of a sheet of paper. It may be modified as desired. The advantage of the rhombus-shape is that it permits the occasionally necessary narrowing of the label, where small folders 60 are used, while maintaining a uniform length, so the distance of the slits from the 65 top edges of the folders may be always the

same, and it also permits labels of all widths to be cut from the same sheets and with the same tools as are used for square labels.

Before the label 16 is mounted on the folder the desired inscriptions or indicia 20 are printed thereon as shown in Fig. 4. The fold or score 18 of the label serves as a guide for the proper location of the inscriptions or indicia. The first line of the inscription should be written, typewritten or printed 25 on the label immediately beneath and close to the fold, or top of the label when folded. It is easy to typewrite the inscription by placing the label unfolded in the typewriter and aligning it with reference to the fold line for in that condition the writing is done upon the central portion of the label instead of near the edge thereof. Hence these labels can be rapidly indexed on the typewriter. Each inscription or index is duplicated by writing it on both sides of the label 30 immediately beneath the fold line and in reverse order, as shown in Fig. 4. Two or three lines of indicia may be written upon each side of the label, for there is ample 35 space for them. The labels are large enough for the inscriptions to be manually written also.

After the label has been cut, folded and the inscriptions placed thereon, it is mounted on the folder as follows, and as illustrated in Figs. 7 to 10. Either of the points or tips 17 of the label is inserted through the slit 15 and it is immaterial which tip is first inserted or at which side of the folder; 40 then the label is placed on the top of the folder, as shown in Fig. 7, with the inside of the fold or score line 18 resting on the top edge of the folder. The corner or tip of the label then is drawn through the slit 45 105 as far as the label will permit, as seen in Fig. 7. The second step of the mounting consists in bending said tip or corner of the label upwardly as shown in Fig. 8. Then the other corner or tip of the label is inserted through the slit from the opposite side, as shown in Fig. 9, and drawn tightly 50 and finally said last-mentioned corner or tip is turned inwardly against the label as 55 shown in Figs. 11 and 12.

This completes the operation of making and mounting the label and it is to be noted that said label fits snugly down on the top edge of the folder and does not project upwardly therefrom, excepting for the thickness of the paper or material forming the label, although the invention is not necessarily limited to a label that does not extend upward somewhat; and manipulation 60 of the folder in the use of the file will not dislodge the label. The label may be removed quickly without tearing it, by first bending back the last inserted projecting corner or tip and inserting a thin blade, 65 like a paper knife, between the label and 70

5 folder on the opposite side of the label and therewith removing the label.

Labels of this character attached in the manner specified offer no appreciable obstruction in their contact with the edges of adjacent folders during the operation of inserting them in the file. The label thus mounted facilitates fingering the folders or sheets by the operator. They can be quickly 10 replaced or changed from one folder to another, whereby one folder may be used for a succession of indicia or labels until it is worn out.

15 While the labels have been herein referred to as being made of paper, they may be made of other material such as thin sheet celluloid, and such celluloid labels be attached and removed in the manner above specified. In the case of celluloid labels the inscriptions may 20 be upon a slip of paper of suitable dimensions inserted under the celluloid which is held in place by the celluloid label acting as a sheath. Also the labels may be of differently colored material and thus provide a 25 graphic signal system in the file without extra expense, and the letters in the printed inscriptions or indicia may be of distinctive colors in order to facilitate identifications and classification.

30 The preferable manner of using this invention is as follows: In a file drawer folders labeled in the manner hereinbefore described are alphabetically arranged with the labels all in position on the right side of the 35 file drawer and the cut-outs consequently all on the left side. Then every fourth folder is taken out of the drawer and the position of its flap is reversed by folding it back upon the other side, the folder turned end for end, 40 and reinserted in its place in the file. This operation results in providing each group of three folders with their labels in the position on the right with a guide on the left in its proper alphabetical order, the guide being 45 visible from either end of the drawer by reason of the open space afforded by the three cut-outs on each side of it.

50 In the use of this file the proper alphabetical classification is preferably maintained regardless of the proportion of folders which are turned end for end. When folders are removed from or added to the file, thus altering the space between the visible labels, any 55 of the folders can be turned to make their labels visible or folders on the visible side can be turned back to the other side. Either side of the file drawer can be used for the visible index, or a part of both sides may be so arranged; or by turning alternate folders 60 end for end, when their contents are of sufficient bulk, the labels on both sides may be made visible. Upon the removal from the file of a folder which serves as a guide, the next folder may be instantly turned, supply-

ing a new guide in proper alphabetical order. 65

The operation of finding in this file is simple and rapid. As the drawer is pulled out the operative's eye moves down the straight line of visible names. The first glance locates either the desired name among the 70 visible guides or the guide giving the alphabetical combination of the first letters of that name. In the latter case the fingers are employed to further spread apart the labels of the little group of three or four which immediately follows the visible guide which 75 requires only a very few seconds.

As noted in Figs. 1 and 2 the inscriptions on the folders can be read from the front or the rear of the series as desired without 80 changing them, because each card has the inscription duplicated and in reverse order. It is also to be noted that the cards can be readily interchanged, reversed, removed and replaced and the labels changed according to 85 the requirements of the filing.

From the foregoing it appears that the 90 folders herein are relatively inexpensive and also the labels, and the inscriptions may be rapidly written on the labels and the labels quickly attached to the folders. There is no danger of the label becoming shifted or detached during manipulation of the file and yet the label can instantly be detached when 95 desired and another label replaced, whereby the use of the folder may be continuous. The labels cause no appreciable increase in the bulk of the file and in cooperation with the cut-outs provided, a large percentage of visibility may be maintained, as shown in Figs. 100 1 and 2, without the employment of any additional equipment.

I claim as my invention:

1. A card-like sheet for vertical filing with an indentation in the top of the sheet 105 near one end thereof, a label folded down over the top of the sheet near the other end thereof, and indicia duplicated on the front and rear sides of said label.

2. A folder for vertical filing with one 110 leaf thereof higher than the other leaf and with an indentation in its top of the higher leaf near one end thereof, and indicia duplicated reversely on the front and rear sides 115 of the higher leaf near the top and near the other end thereof, substantially as set forth.

3. A folder for vertical filing with one leaf thereof higher than the other leaf and with an indentation in the top of the higher leaf near one end thereof, a label folded over the top of the folder near the other end thereof and removably secured thereto, and indicia duplicated reversely on the sides 120 of the label, substantially as set forth.

4. A card-like sheet for vertical filing with a substantially horizontal slit therein near the top, and a label folded centrally 125

- down over the top above said slit with the ends thereof inserted through the slit for holding the label in place.
5. A card-like sheet as set forth in claim 4, with said slit and label located near one end of the sheet, and an indentation in the top near the other end thereof.
6. A card-like sheet as set forth in claim 4, with indicia duplicated in reverse order ¹⁵ on the sides of the label, substantially as set forth.
7. A card-like sheet for vertical filing with a substantially horizontal slit therein near the top, and a label centrally and transversely scored and folded at the score line upon the top of said sheet above the slit with the opposite ends thereof inserted through the slit for holding the label in place.
- In testimony whereof, I have hereunto ²⁰ affixed my signature.

JOHN T. QUIGLEY.
